[57] CLAIM

The ornamental design for a garment hanger, as shown and described.

DESCRIPTION

FIG. 1 is a front elevation view of a garment hanger showing my new design;
 FIG. 2 is a rear elevation view thereof;
 FIG. 3 is a left end elevation view thereof;
 FIG. 4 is a right end elevation view thereof;
 FIG. 5 is a top plan view thereof;
 FIG. 6 is a bottom plan view thereof;
 FIG. 7 is a front elevation view of a garment hanger showing a second embodiment of my new design;
 FIG. 8 is a rear elevation view thereof;
 FIG. 9 is a left end elevation view thereof;
 FIG. 10 is a right end elevation view thereof;
 FIG. 11 is a top plan view thereof;
 FIG. 12 is a bottom plan view thereof;
 FIG. 13 is a front elevation view of a garment hanger showing a third embodiment of my new design;
 FIG. 14 is a rear elevation view thereof;
 FIG. 15 is a left end elevation view thereof;
 FIG. 16 is a right end elevation view thereof;
 FIG. 17 is a top plan view thereof; and,
 FIG. 18 is a bottom plan view thereof.
